PROJECTION APPARATUS

Samuel S. Auchincloss, Darien, Conn., and Clarence A. Woodruff, Westfield, N. J., assignors to New York Quotation Company, New York, N. Y., a corporation of New York

Application June 20, 1939, Serial No. 280,050

4 Claims.

(Cl. 88—24)

This invention relates to improvements in projection apparatus and more particularly relates to apparatus for projecting on a screen the indicia printed on a tape by stock quotation tickers and other printing telegraph apparatus.

Stock quotation projectors, of which there are many different types, commonly include a light source and a lens between which is passed a tape from the ticker. The images of the indicia on the tape are projected onto a screen, usually by means of a series of mirrors, where they are readily visible.

The tape fed from the ticker or printer is moved intermittently and to render the indicia projected on the screen more readily readable, it is necessary to convert the intermittent movement of the tape into a continuous movement between the lens and the light source. Likewise, it is necessary to provide a tape takeup means which is usually made responsive to operation of the ticker or printer so that the tape will be drawn smoothly through the projector and at the same time will not be broken by continued operation of the takeup device when the ticker or printer stops.

Numerous means have been suggested for converting the intermittent movement of the tape into continuous movement, of which the best-known means includes a finger for forming a loop in the tape between the projector and the ticker and responsive to the movement of the tape for controlling operation of the takeup device. A braking element is also provided for exerting tension on the tape to cause it to move smoothly and continuously through the projector. The ticker and the projection equipment are usually mounted in a housing, which emits considerable noise by reason of the operation of the printing and appurtenant mechanism, and the lamp required for adequately illuminating the screen also emits considerable heat which is not dissipated, except by ordinary radiation.

The screen on which the images of the tape indicia are projected usually is a translucent fabric, which is stretched tightly to form a smooth surface. Such screens have excellent light-transmitting properties and are generally more satisfactory than glass screens. However, during humid weather, they absorb moisture and often stretch or wrinkle so that they no longer form a flat surface and, as a consequence, distortion or diffusion of the projected image occurs.

We have discovered means for simplifying the construction of such projectors and for overcoming the tendency of the projection screen to be-

come distorted and for also permitting variation in the size of the projected image as the purpose or environment of the projector demands.

An object of the invention, accordingly, is to provide a simplified means for causing the tape to move smoothly and continuously through a projection device.

Another object of the invention is to reduce the noise of operation of the mechanism and reduce the emission of heat by utilizing it for maintaining the projection screen taut and smooth.

A further object of the invention is to provide means for adjusting the projection device to project different sizes of images as may be desired and for regulating the focus of the device so that sharp images may at all times be obtained.

Another object of the invention is to provide means for maintaining the screen in a dry condition and for preventing dust or other material from accumulating in the projection device whereby decrease in the sharpness and brightness of the projected images is avoided.

Other objects of the invention will become apparent from the description of a typical form of projector embodying the present invention.

One phase of our invention resides in the discovery that the ordinary paper or "Cellophane" ticker tape bears a charge of static electricity which is developed during the manufacture of the tape, or which can be developed during the movement of the tape through a special projector, and that such electrically charged tape will adhere to dielectric material.

We have utilized this phenomenon in order to cause the tape to move smoothly during projection and to maintain it flat in the focal plane of the projection lens whereby sharp focusing of the indicia on the tape, as well as conversion of the intermittent movement of the tape to continuous movement is assured.

In its general aspects, this phase of the invention, therefore, includes the provision of a sheet of transparent dielectric material such as for example, glass, "Lucite," or "Celluloid," between the light source and the projection lens over which the tape is passed and to which it adheres to cause the tape to be held flat, taut and to move continuously during operation of the ticker.

The provision of a sheet of transparent dielectric material for supporting the tape is novel in projection devices. Usually a metallic platform or masking frame is provided for supporting the tape and keeping it out of contact with the condensing lens which normally forms a part of the light source. The condensing lens becomes

highly heated and might ignite or scorch the tape, if they are in contact. Furthermore, the lens is formed of comparatively soft glass and may be easily scratched and thereby reduced in efficiency by contact with the moving tape. Inasmuch as such lenses are expensive, it is apparent that contact between the tape and lens should be avoided.

Another phase of the invention consists in providing a projection screen, associated mirrors, and a projection lens which are adjustable in order to assure sharpness of the projected image, whereby the screen can be moved nearer to or farther from the tape to allow the size of the image to be adjusted. A typical form of adjusting means includes adjustable or replaceable standards for supporting the screen and an adjustable bracket in which the lens is supported slidably and detachably to permit ready focusing and replacement with lenses of greater or lesser focal length.

Thus, if the device is to be used in, for example, a broker's office where a large image is not required, the screen may be placed closer to the projector and a correspondingly smaller image produced. For larger images, the screen may be spaced a greater distance from the projecting lens or a shorter focal length lens used to produce the desired size of image.

An additional phase of the invention resides in the provision of an air cleaning and circulating system whereby air may be drawn through the housing for the light source of the projector to cool the light source and to deliver air heated by the light source to the projection screen for maintaining the latter in a dry and taut condition. The circulated air is passed through a labyrinth where the dust normally carried by the air is largely removed and deposition of dust on the mirrors and other light-transmitting or reflecting surfaces is avoided.

A preferred form of device embodying the invention is provided with heat and sound insulating means, which reduce operating noises and prevent the projection device from radiating heat outwardly on the observers of the device. The air circulating system removes the heat from the device and directs it upwardly over the heads of the observers as it passes from the screen housing.

The various features of our invention set forth generally above, cooperate to form a smoothly-operating, compact and highly efficient projector which requires little attention and which needs to be cleaned and adjusted only rarely.

For a better understanding of the present invention, reference may be had to the accompanying drawings in which:

Figure 1 is a front view of a typical form of projection device embodying the invention shown partly in section to disclose details thereof;

Figure 2 is a sectional view taken on line 2-2 of Figure 1;

Figure 3 is a view in section taken on line 3-3 of Figure 2;

Figure 4 is a view in section taken on line 4-4 of Figure 3;

Figure 5 is an enlarged view of a tape pulling device, shown partly in section and partly broken away;

Figure 6 is an enlarged view in vertical section of the tape support and lens of the device disclosed in Figure 1;

Figure 7 is a view in vertical section of a detail

of the support for the projection screen and mirror housing; and

Figure 8 is a view in section of a resilient mount or cushion for the projection apparatus.

5 A typical form of stock quotation projector including the present invention is illustrated in Figure 1 and includes a cabinet 10 in which is supported a stock quotation ticker 12 of known form, a projection apparatus 13 and a tape pulling mechanism 14. The cabinet 10 consists of a box-like member having therein a bottom partition 15, an intermediate partition 16 and baffle plates 17 and 18 interposed between the partitions 15 and 16. The compartment formed by 10 the partition 16 and the side and top walls of the cabinet 10 are provided with heat insulating and sound deadening material 19 which reduces the noise of operation of the ticker and tape pulling mechanisms to a minimum, and reduces the 15 heat radiated outwardly by the projector apparatus 13. The top of the cabinet 10 is provided with a door 20 through which access may be had to the interior of the cabinet. The door includes a transparent section 20a in alignment with the 20 projection device 13.

Supported on the top of the cabinet 10 by means of a plurality of pipes 21 is a housing 22 for a projection screen 23 and a pair of mirrors 24 and 25 (best shown in Figure 2) which reflect onto the screen 23 the image of the tape A.

30 In order to reduce the sound and vibration resulting from operation of the ticker 12 and the tape puller 14, these elements, together with the projector 13 are supported on a common base plate 26 which is in turn supported on the intermediate partition 16 by means of shock absorbing mounts or cushions 27, best shown in Figure 8. A shock absorbing mount 27 consists of a rubber annulus 28 supported in a cup-shaped element 29 which is secured to the partition 16 by bolts or in any other suitable way. Another cup-shaped element 30 is secured in the rubber annulus 28 and receives the head of a bolt 31 which is provided with a series of lock nuts 32 for locking the bolt in cup-shaped element 30 and locking the platform 26 to the bolt 31.

40 In the form of the invention illustrated, the ticker 12 prints indicia on a tape A and feeds it outwardly with an intermittent movement. The tape A is passed under a roller 33 on the end of an arm 34 (Figures 1 and 6). The arm 34 is supported on a shaft 35 which is rotatable in a bracket 36 projecting outwardly from a housing 37 forming a part of the projection device 13. The shaft 35 carries a mercury switch 38 which is electrically connected to a solenoid 39 (Figure 5) which controls operation of the tape puller 14.

45 The tape puller 14, best shown in Figures 1 and 5, includes a motor 40 supported on a base 41 and a framework 42 consisting of a series of angle iron elements. A pair of parallel shafts 43 and 44 on which are mounted respectively a tape pulling roller 45 and a tape receiving reel 46, are journaled in the frame 42. The shaft 43 is provided with a worm gear 47 which is connected to a sleeve 47a by means of a friction clutch 48. The clutch 48 includes the friction discs 49 and a spring 50 which urges the discs against opposite sides of the worm gear 47. The worm gear 47 is driven by means of a worm 51 which is supported on the shaft 52 of the motor 40. The right hand end of the shaft 43, as viewed in Figure 5, is provided with a pulley 53 which is connected by means of a belt 54 to a pulley 55 which is fastened to the shaft 44. The pulley 55

includes a pair of discs 56 and 57, having curved adjacent surfaces. The disc 57 is provided with a collar 58 which is pinned to the shaft 44. The disc 56 is keyed to the shaft 44 but is slideable axially thereof. A spring 59 normally urges the disc 56 towards the disc 57. The left hand end of the spring 59 bears against an internally threaded collar 60 which receives an externally threaded sleeve 61 having a radially directed flange 62 at the left hand end thereof. The sleeve 62 is fixed to the shaft 44 by means of a set screw 63 and the internally threaded collar 60 may be screwed either to the left or to the right to vary the pressure of the spring 59 against the disc 55, thereby effectively varying the radial distance to which the belt may pass between the discs 56 and 57, and controlling not only the speed of rotation of the reel 46 but forming a slip connection to compensate for increase in effective peripheral speed of the reel during operation.

The tape A is retained in frictional engagement with and moved by the tape pulling roller 45 by means of a pressure roller 64 which is supported on an arm 65 that is pivotally connected to the frame 42. The roller 64 is retained in frictional engagement with the tape A by means of a spring 66 which is connected to the arm 65 and the frame 42. A guide roller 67 may be interposed between the tape pulling roller 45 and the takeup reel 46 and is rotatably mounted on a shaft 68 projecting outwardly from the frame 42.

During operation of the ticker, as previously indicated, the tape A is fed outwardly intermittently, passed beneath the roller 33, across the top of the projector 13, under a tape pulling roller 45 and upwardly to the takeup reel 46 which is, together with the takeup roller 45, driven by the motor 40. So long as a loop of predetermined length is maintained between the ticker 12 and the projector 13, the mercury switch 38 is maintained in open circuit position and the motor 40 drives the tape pulling roller 45 and the takeup reel 46. However, when the ticker slows down or stops, the tape pulling roller 45 tends to decrease the length of the loop in which the roller 33 on the switch arm 34 rides and rotates the switch arm 34 and switch 38 in a counterclockwise direction, thus closing a circuit through the solenoid 39. The solenoid 39 then attracts a lever 69 which is pivotally connected to a U-shaped bracket 70 which supports the solenoid on the frame 42 and separates a clutch element 71 which is keyed to, but slideable relatively to the sleeve 41a from the clutch element 72 on the pulley 53, thus freeing the shaft 43 and the takeup roller 46 from the motor 40 which continues to operate. When the ticker 12 again begins to operate and a sufficiently large loop is formed, the mercury switch 38 rocks into a position opening the circuit and deenergizing the solenoid 39. The spring 73 which is interposed between the lever arm 69 and the outer end of the bracket 70, then swings the lever in a counterclockwise direction, clutching the pulley 53 to the worm gear 47 and the drive shaft 43 to the motor, thus causing the tape pulling roller 45 and the takeup 46 to rotate.

The projector 13 which embodies several of the features of our invention, includes within the housing 37 a projection lamp 74, a reflector 75, a pair of condensing lenses 76 and 77, a mirror 78 which directs the beam of light concentrated by the condensers 76 and 77 upwardly

through a third concentrating lens 79 and a sheet or plate of glass or other transparent dielectric material 80 which forms a platform over which the tape A passes. The plate 80, as best shown in Figure 6, is provided with beveled edges and serves as a means for maintaining the tape A in a flat condition and for holding it in such a way as to convert the intermittent movement of the tape as it leaves the ticker 12 into a continuous movement as it passes through the projector 13. In order to guide the tape over the sheet 80, small flanged guide rolls 81 and 82 may be provided at opposite ends of the housing 37.

The sheet of dielectric material 80 has been found to exert a strong attraction for the tape as it passes thereover, apparently because the tape is electrostatically charged and the sheet 80 being of dielectric material, will tend to take a charge opposite to that of the tape, thereby causing them to adhere. Even when the tape is not previously charged, the friction between it and the plate 80 develops the charge, whereby the tape adheres closely to the plate, requiring a considerable pull to draw it over the plate without the aid of any auxiliary braking or holding means. This adhesion is sufficient to prevent transmission of the intermittent movement of the tape through the projector and thus the tape is moved continuously while held flatly in engagement with the dielectric material and in the focal plane of the lens 83 of the projector. Thus, with this construction, there is no possibility of the tape looping or humping up and thus getting out of focus and causing diffusion or distortion of the image on the screen 23.

The image of the tape A is projected by means of the lens 83 which is detachably and slidably supported in a ring 84 at the upper end of the bracket 85, which is adjustably supported on the outside of the housing 37. The bracket 85 may be provided with an arcuate slot 86 for receiving a bolt 87 projecting outwardly from the housing and provided with a wing nut 88. The bracket may be pivotally supported on the housing 37 by means of a pin 89. This construction permits the lens 83 to be rocked in order to properly center the lens with respect to the portion of the tape being projected. Likewise, the lens 83 may be moved upwardly and downwardly in the ring 84 to properly focus the image on the screen 23 and may be removed to permit substitution of lenses of different focal length for use in the projector, thus allowing the size of the image to be decreased or increased as may be desired.

In order to properly direct the image into the screen 23, the mirrors 24 and 25 in the screen housing 22 may be pivotally mounted on shafts 90 and 91, respectively, which are received in suitable brackets 92 within the housing.

As shown in Figures 1 and 2, proper inclination of the mirror 24 may be obtained by means of a slotted link 93 which is pivotally connected to the right hand end of the mirror 24, and may be locked in position by means of a bolt which passes through the slot in the link 93 and nut 94 on the interior of the housing 22. In a similar way, the mirror 25 may be angularly adjusted by means of a pivotally connected link 95 and a lock bolt and nut 96.

In order to ventilate the housing 37 and to cool the lamp and in addition to maintain taut the projection screen 23, which is suitably formed of a fine mesh silk fabric, we have provided

an air circulation system which causes air to pass around the lamp, thereby cooling the lamp and heating the air and which directs the heated air upwardly into the screen housing 22. This heating and cooling mechanism includes a motor-driven fan 97 which is connected to the side of the projector housing 31 and which draws air upwardly through apertures 98 in the base of the lamp housing 37 from the interior of the cabinet 10. The cabinet 10, as shown in Figures 3 and 4, is provided with a vertically extending duct 99 which communicates with the compartment between the partitions 15 and 16. As indicated previously, the baffles 17 and 18 are disposed between the partitions 15 and 16 and extend partially thereacross from opposite sides of the compartment to form a tortuous passage which communicates with the duct 99 at one end, and the outside atmosphere through the aperture 99a (Figure 3) in the partition 15. The air that is drawn into the chamber formed in the housing 10 through the duct and around the baffles 17 and 18 is thus subjected to numerous changes of direction, and inasmuch as it flows at a comparatively low velocity, any dust entrained therein tends to settle out before passing into the lamp housing 37.

The suction fan 97 withdraws the heated air from the housing 38 and blows it through a conduit 100 into another chamber 101 which is provided with a central baffle 102 around which the gases flow into a T-shaped conduit 103, which communicates with compartments 104 and 105. The compartments 104 and 105 extend transversely of the cabinet 10 at the upper right and left hand corners as viewed in Figure 1, and communicate with the screen chamber 22 through the rear pair of pipes 21 which support the screen chamber in spaced relationship to the cabinet 10. Thus, the heated and cleaned air from the housing 37 is directed upwardly into the screen housing 22, thereby heating the screen 23 and maintaining it in a dry condition. The mirrors 24 and 25 act as baffles to direct the heated air upon the screen 23 and cause a circulation of the air through the housing 22 which prevents dust from the atmosphere from accumulating or settling on the screen or mirrors.

The air circulating system has the additional advantage of removing heated air from near the floor where the cabinet is disposed and from where the screen 23 is being viewed and directing it upwardly toward the ceiling, thereby preventing discomfort to the observers, which might be caused by the heat of the light source.

The pipes 21 which act as conduits for the heated air and also support the screen housing 22, are adjustable with relation to the housing 10 and are likewise replaceable so that the spacing between the screen and housing 22 of the main housing 10 may be varied at will.

As shown in Figures 1 and 7, each pipe 21 is provided with a flanged split sleeve 106 which rests upon the top of the housing 10. The lower portion of the sleeve 106 is threaded to receive a split nut 107 which may be screwed up tightly against a downwardly projecting member 108 which is fixed to the cabinet 10 and then compressed in order to lock the pipe 21 firmly to the chamber 10. It will be understood that the flanged sleeve 106, if desired, may be slid along the pipe 21 to the desired extent so as to permit a limited range of adjustment and that pipes 21 of different lengths may be substituted at will.

in order to vary the space between the screen housing 22 and the main housing 10.

From the foregoing description of a typical form of the invention, it will be apparent that we have provided a simple, efficient type of projector and takeup means for use with stock quotation tickers or printing telegraph apparatuses, and that because of the insulated and air conditioned construction thereof, the device will operate quietly and will not require cleaning or adjustment over long periods of time.

Furthermore, with our construction it is unnecessary to provide mechanical tensioning means for the tape in order to assure smooth continuous movement of the tape through the projector, and because of the control of the tape takeup means there is no danger of breaking or otherwise distorting the tape during projection operation.

It will be understood that there can be many variations made in the details of the device and that the shape and form of the housing, the proportions of the screen and spacing thereof from the projection device can be varied as may be desired, without departing from the invention.

Likewise, the type of lamp housing and condensing lens construction can be varied such as by providing vertically disposed projection system, rather than one in which the lamp housing is disposed at right angles to the axis of the lens, such changes being within the scope of the invention. Therefore, the form of the invention described above should be considered as illustrative only and not as limiting the scope of the following claims.

We claim:

1. In a device for projecting indicia printed on a tape by a stock quotation ticker, the combination of a cabinet, a projector in said cabinet comprising a housing for a source of light, a lens and a support for said tape interposed between said housing and said lens, a housing having a fabric screen therein supported on said cabinet by hollow members communicating with the interior of said cabinet and means for cooling the source of light and maintaining said screen dry comprising a labyrinth communicating with said housing for said light source and said hollow members and means for drawing air from the exterior of the cabinet through said labyrinth to separate dust from the air, through said housing for said light source to cool the latter and directing the warmed air through the hollow members into the housing for said screen to maintain said screen dry and taut.

2. In a device for projecting on a screen images of indicia printed on a tape by a stock quotation ticker, the combination of a cabinet, a projector in said cabinet comprising a housing for a light source communicating with the interior of the cabinet, a housing having a fabric screen on which images are projected, a conduit connecting the interiors of said housings, a compartment in said cabinet forming a labyrinth communicating with the interior and the exterior of the cabinet, means for drawing air from the exterior of the cabinet through said labyrinth to separate dust therefrom, into the interior of the cabinet, through the housing for the light source and into the housing for the screen to cool the light source and maintain the screen dry.

3. The device set forth in claim 2 comprising inclined mirrors in said housing for a light source

for reflecting images projected by said projector onto said screen, said mirrors being supported and arranged in said housing to direct air delivered through said conduit across said screen.

4. The device set forth in claim 2 comprising 5
a labyrinth interposed between said housing for

a light source and said conduit for removing dust from the air prior to delivery to said housing for said screen.

SAMUEL S. AUCHINCLOSS.
